UNITED STATES PATENT OFFICE

ERNEST F. DAVIS, OF MUNCIE, INDIANA, ASSIGNOR TO WARNER GEAR COMPANY, OF MUNCIE, INDIANA, A CORPORATION OF INDIANA

CYANIDING FURNACE

Application filed October 2, 1929. Serial No. 396,614.

My invention relates to improvements in the method of treating ferrous articles in a cyaniding bath which is preferably a molten bath of cyanide.

5 It has for one of its objects the method of treating these articles in a manner whereby the articles may be treated without causing wide fluctuations in the temperature of the molten bath as they are passed therethrough and whereby the articles may be rapidly treated and whereby each article is treated in practically the same manner as the preceding articles in order to maintain a uniformity in the articles to be treated.

10 15 For the purpose of disclosing my invention, I have illustrated certain embodiments thereof in the accompanying drawings, in which:

Fig. 1 is a plan view of the furnace setting 20 the pot being removed;

Fig. 2 is a sectional partial view on the line 2—2 of Fig. 1;

Fig. 3 is a transverse sectional view of the furnace, and

25 Fig. 4 is a front elevation of the apparatus, partially in section.

In the embodiment illustrated, the furnace comprises the fire chamber 1, which is surrounded by suitable end walls 2 and side walls 30 3 built up of fire brick. The chamber is provided with burner openings 4 through which may project fuel supplying burners, and the firing chamber communicates with a suitable chimney 5 by means of a flue 6. Baffles 7 are 35 built opposite each of the burner openings to direct or spread the flame.

The cyanide tank 8 is supported in the top 40 of the fire chamber and to this end is provided with flanges 9 adapted to rest on the top edge of the walls surrounding the chamber. This tank has a greater length than width and is adapted to contain the molten bath which is maintained at the proper temperature by the burners beneath the same.

45 The articles to be treated are deposited at

one end of the tank 8 and passed to the opposite end of the tank by means of a suitable conveyor. This conveyor comprises a screw 10 supported in suitable bearings 11, hung by bearing supports 12, from a supporting beam 50 13 above the tank. The screw may be rotated at any desired speed from a controllable source of power in operation.

The articles 14 to be heat treated are suspended at one end of the screw, at the right 55 of the drawings in the present instance, from supporting hooks 15, and as the screw is rotated are progressively moved towards the opposite end of the tank. A substantially continuous feeding of the articles may be 60 maintained by one operator depositing the articles on the receiving end of the screw and another operator removing them from the delivery end of the screw after they have 65 passed through the bath.

In actual practice the furnaces are built 70 in pairs with right and left screws feeding toward a common delivery point so that one operator may control the removal of the material from two tanks.

I claim the following:

1. The method of treating ferrous articles in a molten bath of cyaniding material, which consists in the provision of an elongated pot 75 containing the treating cyaniding material, maintaining the temperature of said bath at a molten and substantially uniform point by heaters located beneath the pot, depositing the ferrous articles to be treated in small quantities at one end of the pot at spaced intervals and progressively moving said small quantities of articles through the bath while maintaining said spaced intervals by means of a constantly moving conveyor mounted above the bath.

2. The method of treating ferrous articles in a molten bath of cyaniding material, which consists in the provision of an elongated pot 85 containing the treating cyaniding material, maintaining the temperature of said bath at 90

a molten and substantially uniform point by
heaters located beneath the pot, depositing
the ferrous articles to be treated in small
quantities at one end of the pot at spaced in-
5 tervals and progressively moving said small
quantities of articles through the bath while
maintaining said spaced intervals by means
of a constantly moving screw conveyor
mounted above the bath and from which the
10 articles are supported in the bath.

In witness whereof, I ERNEST F. DAVIS
have hereunto set my hand at Muncie, Indiana,
this 27th day of September, A. D. one
thousand nine hundred and twenty-nine.

15 ERNEST F. DAVIS.
